UNITED STATES PATENT OFFICE.

SAMUEL C. BELKNAP AND THEODORE H. FYE, OF ZANESVILLE, OHIO.

OVERSHOE.

SPECIFICATION forming part of Letters Patent No. 313,161, dated March 3, 1885.

Application filed July 23, 1883. (No model.)

To all whom it may concern:

Be it known that we, SAMUEL C. BELKNAP and THEODORE H. FYE, of Zanesville, in the county of Muskingum and State of Ohio, have 5 invented certain new and useful Improvements in Overshoes; and we do hereby declare the following to be a full, clear, and exact description of the invention, such as will enable others skilled in the art to which it appertains to 10 make and use the same.

Our invention relates to an improvement in rubber overshoes, the object being to provide this class of goods with ice-creeper, and to provide for the removal of the same when not 15 needed.

With this object in view our invention consists in the combination, with a rubber overshoe, of a removable ice-creeper consisting of a metallic plate provided with points arranged 20 to project through the sole or heel of the shoe.

In the accompanying drawings, Figure 1 is a perspective view of a sandal embodying our invention. Fig. 2 is a reverse plan view thereof. Fig. 3 is a view of the sandal in vertical transverse section. Fig. 4 is a detached view 25 of one form which the creeper may assume, and Fig. 5 is a detached view of a dummy.

In the drawings our invention is shown as 30 applied to a sandal or foot-hold, A; but it is apparent that it is applicable to all styles of overshoes.

The ice-creeper consists of a metallic plate, B, having points C depending from its lower 35 face. These points may vary in number and in position, and they may be attached to or made integral with the plate, as found most desirable. The plate itself may assume various forms, as fancy and convenience may 40 dictate. The points are arranged to project through holes D, formed either in the heel or sole of the shoe, or both.

The dummy is employed to fill the holes D when there is no occasion for the use of the 45 creeper. It consists of a plate, E, of molded

rubber or metal, provided with projections F, adapted to fill and close the holes D without projecting through them. If desired, the plate may be provided with teeth instead of points; and the dummies made accordingly. 50

The shoe requires no especial adaptation to fit it for our improved ice-creeper, and it receives the minimum of injury therefrom.

The creeper and dummy are easily exchanged each for each, and they do not dis- 55 commode the wearer of the shoe.

In Letters Patent No. 278,308, granted to us May 29, 1883, the invention consists of a half-sole and devices for removably securing the half-sole to the shoe. Between the half-sole 60 and the sole of the shoe is placed an ice-creeper. We would therefore have it understood that we make no claim in this patent broad enough to cover the invention shown and described in our patent as above recited. 65

The improvement herein described is much simpler and cheaper in its construction than that described in our patent.

Instead of employing a half-sole with devices for securing it to the shoe, we use an ordinary overshoe or sandal and attach the ice-creeper thereto. 70

Having thus fully described our invention, what we claim as new, and desire to secure by Letters Patent, is—

The combination, with a rubber overshoe, 75 of a removable ice-creeper consisting of a plate provided with depending points arranged to project through holes formed in the sole or heel of the shoe, substantially as set forth.

In testimony whereof we have signed this specification in the presence of two subscribing witnesses.

SAMUEL C. BELKNAP.
THEODORE H. FYE.
